UNITED STATES PATENT OFFICE.

MILFORD JAMES ATKINSON, OF MIMICO, ONTARIO, CANADA.

DESIGN FOR AN AUTOMOBILE-TIRE.

57,071.

Specification for Design.

Patented Feb. 8, 1921.

Application filed May 7, 1920. Serial No. 379,680. Term of patent 14 years.

To all whom it may concern:

Be it known that I, MILFORD JAMES ATKINSON, a subject of the King of Great Britain, and resident of Symons street, in the town of Mimico, in the county of York, in the Province of Ontario, in the Dominion of Canada, have invented a new, original, and ornamental Design for an Automobile-Tire, of which the following is a specification, reference being had to the accompanying drawings, forming part thereof.

In the drawings Figure 1 is a plan view of a portion of an automobile tire.

Fig. 2 is a cross sectional view taken on the line A—A of Fig. 1.

What I claim is:

The ornamental design for an automobile tire as shown.

Signed at Toronto, Ontario, this 24th day of April, 1920.

MILFORD JAMES ATKINSON.
